United States Patent

Des. 240,033
Patented May 25, 1976

240,033

MEMO BOX

William Macowski, Caldwell, N.J., assignor to Ketcham & McDougall, Inc., Roseland, N.J.

Filed Mar. 6, 1975, Ser. No. 555,978

Term of patent 14 years

Int. Cl. D19—02

U.S. Cl. D19—92

FIG. 1

FIG. 2

FIG. 3

FIG. 4

FIG. 5

FIG. 6

FIG. 1 is a perspective view of a memo box showing my new design;

FIG. 2 is a top plan view;

FIG. 3 is a front elevational view;

FIG. 4 is a left-side elevational view, the side not shown being a mirror image thereof;

FIG. 5 is a bottom plan view; and

FIG. 6 is a rear elevational view.

I claim:

The ornamental design for a memo box, as shown and described.
